UNITED STATES PATENT OFFICE.

MILLARD SMITH, OF ST. LOUIS, MISSOURI

METALLIC WINDOW.

1,101,214

Specification of Letters Patent. Patented June 23, 1914.

Application filed April 21, 1913. Serial No. 782,584.

To all whom it may concern:

Be it known that I, MILLARD SMITH, a citizen of the United States of America, and a resident of the city of St. Louis and State 5 of Missouri, have invented certain new and useful Improvements in Metallic Windows, of which the following is a full, clear, and exact description; reference being had to the accompanying drawings, forming part of 10 this specification.

My invention relates to a metallic window, and has for its object to provide novel structural features in windows of this kind by which the joints between the window 15 sashes and the window frame jambs may be automatically tightened.

Figure I is a view mainly in elevation and partly in vertical section of my metallic windows, both the frame and the sashes being 20 partially broken away. Fig. II is a vertical section through my window. Fig. III is an enlarged vertical section taken on irregular line III—III, Fig. I, the upper portion of this view being taken through the lintel 25 of the window frame, the top rail and a portion of a stile of the upper sash and the lower portion of the view being taken through the lower rail of the bottom sash and the sill. Fig. IV is a view partly in 30 elevation and partly in vertical section of one of the upper corners of the window frame and the adjacent upper corner of the upper sash. Fig. V is an enlarged elevation looking at the inside face of one of 35 the window frame jambs and the adjustable parting strip member, portions being broken out and shown in section. Fig. VI is a horizontal section taken on line VI—VI, Fig. V. Fig. VII is a horizontal section 40 taken on line VII—VII, Fig. V. Fig. VIII is a fragmentary view of one of the window frame jambs illustrating the screw receiving bushings therein. Fig. IX is a view of a portion of one of the adjustable parting 45 strip members illustrating the elongated apertures therein. Fig. X is an elevation of a fragment of one of the adjustable sash stops. Fig. XI is an enlarged section of one of the screw receiving bushings as it appears 50 previous to application to the jamb of the window frame. Fig. XII is an enlarged section illustrating one of the screw receiving bushings applied to the window frame jamb.

65 The preferred form of the invention comprises an upper sash A and a lower sash B,

both of said sashes being slidably fitted to a window frame composed of a lintel C, a sill D and jambs E. All of these parts are of sheet metal and box-like form. The lintel C, (Figs. II and III), is provided with a longitudinal groove 1 and a shoulder 2 for the reception of the upper edge of the top rail of the upper sash. The top rail of the upper sash is provided with a longitudinal flange 3, which extends into the groove 1 in the lintel. The upward movement of the top sash is limited by abutment screws 4 adjustable in corner braces 5 in the sash and adapted to engage the lintel C. The sill D is formed with a vertical abutment 6 and an abutment 7 inclined toward said vertical abutment, and the bottom rail of the lower sash has abutments 8 and 9 adapted to be wedged between the sill abutments 6 and 7. 75 The inclined sash abutment 8 rests on the inclined sill abutment 7 and when these inclined abutments are engaged with each other, the vertical abutment face 9 on the lower sash is forced against the vertical sill abutment 6, to effect a tight joint between the sash and sill. To insure a tight joint between the lower sash and the sill, the abutment screws 4 in the top rail of the upper sash may be adjusted so that the lower sash will firmly engage the sill abutments when the sashes are locked by a suitable sash fastener 10. Each jamb E, (Fig. VI), includes an outer fixed stop F, an adjustable inner stop G, the latter being secured to the jamb, as will be hereinafter described. The fixed stop F is formed with a vertical guide tongue 12 and a vertical groove 13.

H designates a yieldable parting strip 95 member in the form of a sheet metal plate arranged between the sashes and jamb E, and having one of its margins firmly held to the jamb by screws 14 passing through slots 15 in the parting strip member, (Figs. V, 100 VII and IX). The middle portion of the yieldable parting strip member H is bowed away from the jamb and its free vertical edge is slidably fitted in the vertical groove 13, (Fig. VI).

The sashes are closely fitted to a longitudinal rib h at the center of the parting strip member and loosely fitted to the stops on the jambs so that a tight joint is obtained between the sashes and the parting strip. 110 Each sash is provided with a tongue 16 loosely fitted to one of the stops F or G, and

a tongue 17 arranged in a vertical groove 18 back of the bead h on the parting strip member. The tongues 17 on the sashes are interlocked with the parting strip member H so that the latter will yield to compensate for variations in the dimensions of the sashes.

The adjustable stop 6 is preferably a channel shaped strip having a guide tongue 10 12' and provided with slots 19 for the reception of screws 20. The said adjustable stop G is also formed with openings 14' through which a screw driver may be passed in adjusting the screws 14 which secure the 15 parting strip member to the jamb. The parting strip member H is provided with slots 20' (Figs. V and IX), through which the screws 20 pass.

Nuts or bushings N, riveted to the jamb 20 are provided with screw threaded apertures for the reception of the screws 14 and 20, (Figs. XI and XII). Each nut N consists of a head 22 having a concave face 23 and a thin tubular extension 24 projecting from 25 said concave face. The tubular extension 24 is passed through an aperture in the jamb and upset as shown in Fig. XII, so as to force the thin wall of the jamb against the concave face of the nut, thereby countersinking 30 the upset portion of the nut into the sheet metal of the jamb.

I claim:

1. In a window, a frame including a jamb, and a yieldable parting strip member extending across the face of said jamb and bowed outwardly therefrom for the purpose described, and a sash interlocked with said yieldable parting strip member.

2. In a window, a frame including a jamb, 40 a yieldable parting strip member rigidly secured near one of its vertical margins to said jamb, the other vertical margin of said yieldable parting strip member being loosely and slidably fitted to said jamb and the middle portion of said yieldable parting strip member being bowed away from said jamb, and a sash interlocked with the yieldable middle portion of said yieldable parting strip member.

3. In a window, a frame, a yieldable part-

ing strip member in the form of a bowed metallic plate extending across said frame and secured adjacent one of its margins to said frame, and sashes loosely fitted to said frame and slidably fitted to the bowed portion of 55 said yieldable parting strip member, each of said sashes being interlocked with said yieldable parting strip member.

4. In a window, a frame including a jamb, a yieldable parting strip member secured to said jamb, said yieldable parting strip member being in the form of a bow having a vertical groove, and a sash movable toward and away from said jamb, said sash having a tongue extending into said groove 60 65 so as to interlock the sash with the yieldable parting strip member.

5. In a window, a frame including jambs and stops, sashes loosely fitted to said stops, and a yieldable parting strip member in the 70 form of a metallic plate interposed directly between said sashes and one of said jambs, said sashes being interlocked with and closely fitted to the yieldable middle portion of said yieldable parting strip member. 75

6. In a window, a frame including a jamb, a stop on said jamb, and a second stop adjustably secured to said jamb, a slotted parting strip member in the form of a sheet metal plate overlapping said stops, and 80 means for adjustably connecting said parting strip member directly to said jamb adjacent one of its margins, said means including screws which pass through the slots in said parting strip member. 85

7. In a metallic window, a frame including a jamb, a stop provided with slots, and screws passing through said slots and connecting said stop to said jamb, a parting strip member having one of its margins arranged between said stop and jamb, the said margin being provided with slots, and screws passing through the last named slots and connecting said parting strip member to said jamb. 90

MILLARD SMITH.
